UNITED STATES PATENT OFFICE.

FRANK E. EWLES, OF MEDINA, NEW YORK.

SPRING-SUPPORT FOR FURNITURE.

SPECIFICATION forming part of Letters Patent No. 703,776, dated July 1, 1902.

Application filed January 23, 1902. Serial No. 90,932. (No model.)

To all whom it may concern:

Be it known that I, FRANK E. EWLES, a citizen of the United States, residing at Medina, in the county of Orleans and State of New York, have invented new and useful Improvements in Spring-Supports for Furniture; and I do hereby declare the following to be a full, clear, and exact description of the invention, such as will enable others skilled in the art to which it appertains to make and use the same.

My invention relates to an improvement in spring-supports for furniture, and more particularly to the means for connecting the convolute springs with the supports secured to the framework.

The object of this invention is to provide a connection for the springs which is simple and durable in construction, which permits the springs to be attached to their supports with ease and security, and which when the weight is applied to the support tends to more effectually clamp the springs and secure the same to the supports.

As will be apparent from the following description, the invention is also applicable to carriage and car seats, mattresses, and all articles having coil-springs designed to be secured to a support.

To this end the invention consists in certain novel details of construction and combination and arrangement of parts, as will be hereinafter described, and pointed out in the appended claims.

Referring to the drawings, Figure 1 is a top plan view of a chair-seat frame having the herein-described improvement attached thereto. Fig. 2 is a vertical section taken on line *x*-*x*, Fig. 1. Fig. 3 is an enlarged perspective view of a portion of one of the wire supports having one of the convolute springs connected therewith. Fig. 4 is a vertical section, on an enlarged scale, taken on line *y*-*y*, Fig. 2.

Like numerals of reference refer to like parts in the several figures.

The numeral 1 designates the chair-seat frame, which may be of any suitable form or construction. Secured to this frame are the wire supports 2, which consist of a horizontally-disposed center portion 3, preferably po-

sitioned below the plane of the chair-seat frame, and upwardly-inclined end portions 4 at either end, which terminate in hooks 5, embedded in the seat-frame for securely fastening the supports thereto. Between its ends, at such points where it is desired to secure the convolute springs forming the cushion, I coil the wire upwardly above its longitudinal axis into an eye 6, continuing the coil to form a second eye 7, which is disposed on a vertical plane with the eye 6 and below the longitudinal axis of the wire. The wire is thus provided with a double eye defining the figure 8, and in these eyes the small end 65 of the convolute springs is secured.

The springs 9 are of the ordinary form usually employed in upholstering, having their upper coil 10 largest and the coils gradually reduced in diameter downwardly, with the 70 smallest or lower coil 11 terminating in a diametrically-disposed extension 12, crossing the axis of the spring. When connecting the spring to the wire support, the diametrically-disposed extension 12 is passed through the 75 upper eye 6 as far as permissible. The projecting end is then bent into the form of a hook 13 and the end thereof passed through the lower eye 7. A very simple connection is thus formed, which is easily manipulated 80 and which is effectual in the performance of all its functions.

The upper ends of the springs are preferably connected together and to the framework by cords 14, the cushioning, of course, 85 being built up from this point, as is common in upholstering.

It is evident that with the construction shown the liability of the springs becoming detached from the supports is entirely obviated, as the connection will not permit their turning, and the weight of a person will cause the supports to sag slightly, which will close up the eyes 6 and 7, in which the springs are held, and clamp the same more securely. 90 After the eyes have closed around the springs and become set there is no further liability of sagging, and the cushion will under all conditions of usage retain its proper shape. 95

Having thus described my invention, what I claim is—

1. In a spring-seat, the combination of a

support having an eye extending above and an eye extending below the same on a vertical plane, and a spring having its lower end bent upon itself and arranged to enter the upper eye from one side of the support and the lower eye from the other side of the same, substantially as set forth.

2. In a spring-seat, the combination of a wire support having two eyes formed on opposite sides thereof, and a spring having its connecting end bent upon itself and arranged to enter one eye from one side of said support and the other eye from the opposite side of the same, substantially as set forth.

15 3. In a spring-seat, the combination of a wire support having an eye above and an eye below its longitudinal axis, and a spring having its lower end terminating in a hook which enters the upper eye from one side and the

lower eye from the opposite side of said support, substantially as set forth.

4. In a spring-seat, the combination of a support composed of wire bent upon itself to form an eye above and an eye below its longitudinal axis, and a spring having a hook at its lower end disposed diametrically to cross the axis of the same, said hook passing through the upper eye from one side of the support and through the lower eye from the opposite side thereof, substantially as set forth.

30 In testimony whereof I have signed this specification in the presence of two subscribing witnesses.

FRANK E. EWLES.
